Application filed August 29, 1900. Serial No. 28,479. Term of patent 7 years.

To all whom it may concern:

Be it known that I, VIOLA E. KENT, a citizen of the United States, residing at Kalamazoo, in the county of Kalamazoo and State of Michigan, have invented and produced a certain new and original Design for Meat or Vegetable Choppers; and I do declare the following to be a full, clear, and exact description of the invention, such as will enable others skilled in the art to which it appertains to make and use the same.

The invention relates to a new and original design for meat or vegetable choppers; and it consists of a design of the shape and configuration shown in the accompanying drawing, in which the figure is a perspective view of the chopper.

The leading feature of the design comprises an annular band 1, terminating in an annu-

lar downwardly-projecting corrugated extension 2, the corrugations 3 of which are provided with triangular facets 4 at their upper ends and are tapered outwardly from their upper to their lower ends. Projecting upwardly from the band 1 is a handle-frame 5, the upper end of which is provided with a grip 6.

What I claim is—

The design for a meat or vegetable chopper as herein shown and described.

In testimony whereof I have hereunto set my hand in presence of two subscribing witnesses.
